US0D1019221S

(12) **United States Design Patent** (10) **Patent No.:** **US D1,019,221 S**
(45) **Date of Patent:** **** Mar. 26, 2024**

(54) **STORAGE RACK**

(71) Applicant: **Shenzhen Jiying Technology Co., Ltd.**,
Guangdong (CN)

(72) Inventor: **Jinlin Zhuang**, Guangdong (CN)

(73) Assignee: **Shenzhen Jiying Technology Co., Ltd.**,
Guangdong (CN)

(**) Term: **15 Years**

(21) Appl. No.: **29/900,771**

(22) Filed: **Aug. 24, 2023**

(30) **Foreign Application Priority Data**

Jun. 6, 2023 (CN) 202330345714.6

(51) **LOC (14) Cl.** **21-03**

(52) **U.S. Cl.**

USPC **D6/681**

(58) **Field of Classification Search**

USPC D6/664, 672, 673, 675, 675.1, 675.2,
D6/675.3, 681, 681.2; D7/600.4; D32/58

CPC A63B 9/00; A63B 17/04; A63B 2209/00;
A63B 2210/00
